UNITED STATES PATENT OFFICE.

HARRY B. HULL, OF DAYTON, OHIO, ASSIGNOR TO DELCO-LIGHT COMPANY, OF DAYTON, OHIO, A CORPORATION OF DELAWARE.

REFRIGERATING APPARATUS.

Application filed April 30, 1923. Serial No. 635,519.

To all whom it may concern:

Be it known that I, HARRY B. HULL, a citizen of the United States of America, residing at Dayton, county of Montgomery, 5 State of Ohio, have invented certain new and useful Improvements in Refrigerating Apparatus, of which the following is a full, clear, and exact description.

This invention relates to mechanical motion or power transmission devices, and particularly to devices for transmitting motion from a driving member to a driven member while providing for hermetically sealing the driven member.

15 It is an aim of the invention to transmit motion to a hermetically sealed mechanism in a simple and efficient manner and with the least wear to a part of the enclosure of the mechanism.

20 In certain aspects this invention provides improvements in the type of apparatus shown in the copending application of Jesse G. King, Serial No. 400,894, filed August 3, 1920. That application discloses a 25 driving member including a crank shaft and a crank, and a pressure pump including a reciprocating member adapted to be driven by another crank. The driving crank is connected with a reciprocating 30 member by means of an intermediate crank shaft including a portion coaxial with the driving crank shaft and provided at one end with a crank for engaging the reciprocating member. This intermediate crank shaft 35 is bent intermediate its ends so as to provide a portion which is oblique to the axis of the driving crank shaft, and the end of this oblique portion is received by a bearing located in an eccentrically and obliquely 40 disposed recess in the driving crank. The bend is of course such that the oblique portion of the intermediate crank shaft will be in true alignment with the said recess in the driving crank. The bent crank shaft is 45 enclosed by a housing a portion of which is flexible and hermetically seals the crank shaft and a bearing which the pressure pump provides for it.

50 It is among the objects of the present invention to simplify the manufacture of apparatus of the type disclosed in said copending application in order to facilitate the alignment of the oblique portion of the intermediate crank shaft with the eccentrically and obliquely disposed recess in the

driving crank. This aim of the invention is preferably accomplished by making the oblique portion of the crank shaft and the coaxial portion in separate pieces, and by providing a simple driving connection between the two shaft portions. In this way the separate portions of the crank shaft adjust themselves to their respective bearings.

55 Other and further objects and advantages of the present invention will be apparent from the following description, reference being had to the accompanying drawings, wherein a preferred embodiment of the present invention is clearly shown.

In the drawings:

70 Fig. 1 is a side view partly in section of a pressure pump provided with the present invention;

Fig. 2 is a fragmentary top plan view of the joint connecting the shaft portions; 75 and

Fig. 3 is an end view of the obliquely disposed shaft portion as shown in Fig. 1.

70 The pressure pump includes a frame 20 providing an eccentric crank housing and 80 a gear housing 22 separated by a wall 23. Gear housing 22 is enclosed by an end wall 24 provided with an opening 25 large enough to provide for removal of parts of the pump driving mechanism. The opening 25 is closed by a cover member 26 attached by screws 27, the joint between members 24 and 26 being sealed by packing 28.

85 The end member 26 is provided with a hollow cylindrical extension 30 providing 90 bearings 31 and 32 for a hollow crank shaft 33 having an eccentrically and obliquely disposed hole 34 adapted to receive a hollow cylindrical bearing 35 the diameter of which is increased at 36 to provide for receiving 95 a portion of the motion transmitting intermediate crank shaft to be described. Driving crank shaft 33 includes an outwardly flaring flange 37 provided with gear teeth 38 adapted to mesh with a worm gear 39 100 rotatably supported by the frame 20 and driven by any suitable power means such as an electric motor.

105 The frame 20 supports a cylinder block 40 providing cylinders 41 and 42. The block is attached by screws such as 43, and the joint between the block and the frame is sealed by packing 44. A piston such as 45 reciprocates in each cylinder and the two pistons are connected by connecting rods including 110

2
 eccentric straps 46 and 47 which cooperate with eccentrics 48 and 49 respectively. These eccentrics are angularly spaced 180° and have a common hub 50 attached by a 5 key 51 to crank shaft portion 52 which is coaxial, with the driving crank shaft 33. Crank shaft portion 52 is rotatably supported by bearings 53 and 54, bearing 53 being provided by a wall of the frame 20 and the 10 bearing 54 being removably supported by the partition wall 23. Bearing 54 serves as a cover for an opening 55 providing for removal of the crank shaft portion 52. The bearing member 54 is secured in position by 15 screws 56 and the joint between the partition wall 53 and bearing 54 is sealed by packing 57.

The obliquely disposed crank shaft portion designated by numeral 60 and includes 20 a reduced end 61 serving as a journal which is received within a thimble-like bushing or bearing 35. The joint between the crank shaft portions 52 and 60 is provided by notching the end of shaft portion 60 to provide 25 vide. tongues 62, 63, 64, and 65 located 90° apart. The end faces of these tongues are all perpendicular to the shaft portion 60. Tongues 62 and 64 are received by notches 66 and 68 respectively provided in one end 30 of the shaft portion 52, notches 66 and 68 are diametrically opposed and the end or bottom surfaces defining these notches are in alignment and are oblique to the axis of shaft 52 by an amount which is equal to 35 the acute angle between shaft portions 52 and 60. The tongues 63 and 65 are received by notches 67 and 69 respectively provided in shaft 52. Notches 67 and 69 are diametrically opposed and arranged oblique to the 40 axis of shaft 52 by an amount equal to the angularity of shaft 60. The tongues are slightly loosely received by the notches, there being sufficient clearance to permit the shaft 52 to be located by its bearings and the shaft 45 60 by its bearing 35 without interference by the tongue-and-groove joint.

In order to seal the motion transmitting shaft portions entirely and the bearings for supporting said shaft portions there is provided 50 a flexible sleeve 70 commonly known as a sylphon. The sleeve 70 is attached at one end to the bearing 35 and at the other to a washer 71 which is clamped against a bearing member 54 by means of a clamping 55 ring 72 and the screws 56. The joint between the washer 71 and the bearing 54 is sealed by packing 73.

It is therefore apparent that the crank case chamber 21 and the motion transmission shaft portions 60 and 52 are hermetically sealed to prevent the escape of compressed gas from the crank case of the compressor. The crank shaft 52-60 is enclosed by a housing which includes a flexible portion 85 which permits one portion of the crank

shaft to revolve about the axis of the other portion. This flexible portion of the housing is the flexible sleeve 70 which is permanently attached by brazing or soldering to the bearing 36 and to the washer 71.

The air pump is particularly adapted for refrigerating apparatus and is of the type in which the gas to be compressed enters at 80, passes through the pistons and is discharged through an outlet 81.

A power transmitting mechanism is so constructed that it may be readily disassembled. After removing the screws 27 the housing end cover or driving crank shaft bearing member may be removed from the frame 20. Then the crank shaft 33 may be moved by an outward and oblique movement so that the bearing 35 will be withdrawn from the recess 34. By removing screws 56 the crank shaft 52-60 with its bearing 54 and flexible housing can be removed in assembled relation, the eccentrics 48 and 49 remaining in position and supported by the eccentric straps 46 and 47, respectively. After removing the screws 43, the cylinder block, pistons, straps and eccentrics can be removed from the frame 20. The frame 20 is provided with a removable plug 82 adjacent the bearing 53. By removing this plug access is provided to the right hand end of shaft 52 so that it may be tapped by a hammer to assist in loosening the bearing 54.

Lubrication is provided by placing a quantity of oil in each chamber 21 and 22 as indicated by level lines 90 and 91. The eccentric straps will be lubricated by splashing into the oil under level 90 and throw oil upon the bearing 54 and on the shaft 52. Some oil will find its way to bearing 53, and to bearing surface of 54 through hole 92.

Oil in chamber 22 will be splashed by gear 38 and some of it will enter hole 93 and lubricate the surfaces of bearings 31 and 32. The bearings 35 will be lubricated by oil entering at 94 or through side holes 95 and running along the bearing 35 to the recess 34.

While the form of mechanism herein shown and described constitutes a preferred form of embodiment of the invention, it is to be understood that other forms might be adopted, all coming within the scope of the claims which follow.

What I claim is as follows:

1. In a mechanical movement device, the combination with a driving shaft and crank carried thereby having an eccentrically and obliquely disposed driving portion; of a driven mechanism; means for connecting the driving shaft and driven mechanism including separate obliquely disposed shaft portions, one aligned with the axis of the driving shaft and the other with the axis of said driving portion, and provisions for connecting said shaft portions permitting 120

the adjustment of the shaft portions in said positions of alignment; and a housing for said shafts including a flexible member permitting one shaft portion to revolve about 5 the axis of the other portion.

2. In a mechanical movement device, the combination with a driving shaft and crank carried thereby having an eccentrically and obliquely disposed recess; of a driven mechanism; means for connecting the driving shaft and driven mechanism including separate obliquely disposed shaft portions, one aligned with the axis of the driving shaft and the other with the axis of said driving 10 recess, and provisions for connecting said shaft portions permitting the adjustment of the shaft portions in said positions of alignment; and a housing for said shafts including a flexible member permitting one shaft 15 portion to revolve about the axis of the other portion.

3. In a mechanical movement device, the combination with a driving shaft and crank carried thereby having an eccentrically and obliquely disposed driving portion; of a driven mechanism; means for connecting the driving shaft and driven mechanism including separate obliquely disposed shaft portions, one aligned with the axis of the 20 driving shaft and the other with the axis of said driving portion, and a tongue-and-groove joint between the portions of such looseness as to permit the adjustment of the shaft portions in said positions of alignment; and a housing for said shafts including a flexible member permitting one shaft 25 portion to revolve about the axis of the other portion.

4. In a mechanical movement device, the combination with a driving shaft and crank carried thereby having an eccentrically and obliquely disposed driving recess; of a driven 30

mechanism; means for connecting the driven mechanism and driving shaft including a shaft portion in alignment with the 45 driving shaft and a portion received by said driving recess; means for hermetically sealing said mechanism and connecting shaft portions; means for lubricating said connecting shaft; and separate means for lubricating the driving crank shaft and driving 50 recess.

5. In a mechanical movement device, the combination with a driving shaft and crank carried thereby having an eccentrically and obliquely disposed driving recess; of a driven mechanism; means for connecting the driven mechanism and driving shaft including a shaft portion in alignment with the 55 driving shaft and a portion received by said driving recess; means for hermetically sealing said mechanism and connecting shaft portions; including a flexible part; means for enclosing the driving crank shaft and the flexible part. 65

6. In a mechanical movement device, the combination with a driving shaft and crank carried thereby having an eccentrically and obliquely disposed driving recess; of a driven mechanism; means for connecting the driven mechanism and driving shaft including a shaft portion in alignment with the 70 driving shaft and a portion received by said driving recess; means for hermetically sealing said mechanism and connecting shaft portions; including a flexible part; and means providing a bearing for the driving crank shaft and the flexible part. 75

In testimony whereof I hereto affix my signature.

HARRY B. HULL.
